UNITED STATES PATENT OFFICE.

GEORGE FECZKO, OF BRADDOCK, PENNSYLVANIA.

WIRE-DRAWING MACHINE.

1,095,320.

Specification of Letters Patent.

Patented May 5, 1914.

Application filed May 29, 1913. Serial No. 770,748.

To all whom it may concern:

Be it known that I, GEORGE FECZKO, a subject of the King of Hungary, residing at Braddock, in the county of Allegheny and State of Pennsylvania, have invented certain new and useful Improvements in Wire-Drawing Machines, of which the following is a specification.

The present invention relates to improvements in wire drawing machines, and is designed with the purpose of producing a machine for reducing the gage of wire in an efficient, facile and comparatively rapid manner.

The invention consists essentially in combining in a single machine, a succession of gage-reducing devices by means of which the gage of the wire may be successively reduced as it is drawn out, and in certain novel forms and combinations and arrangements of parts for actuating the instrumentalities, and adjusting the parts of the machine in the performance of its functions.

In the accompanying drawings I have illustrated one complete example of the physical embodiment of the machine constructed according to the best mode I have so far devised for the practical application of the principles of the invention.

Figure 1 is a side elevation of a machine embodying the invention. Fig. 2 is an elevation of the machine from the side opposite Fig. 1. Fig. 3 is a top plan view. Fig. 4 is a transverse vertical section on line 4—4. Fig. 5 is a vertical section on line 5—5 Fig. 2. Fig. 6 is a fragmentary sectional view showing in detail elevation a guide roll for the wire as it is wound upon a drum, and means for adjusting the roll with relation to the drum. Fig. 7 is a detail perspective view of a tool employed in starting to wind the end of the wire on the drums preparatory to drawing the wire, the employment of the tool being only temporary for the purpose of starting the operation of drawing or reducing the wire.

In the preferred embodiment of the invention I employ a plurality of winding drums arranged as in Figs. 1 and 3 and designated 1, 2, and 3. These drums are supported on their respective shafts 4, 5, 6, which are journaled in a frame 7 projecting upright from the table 8. The table 8 is a suitable altitude from the floor and is supported upon corner legs 9, the whole preferably being metal. The drum shafts 4, 5, 6, are driven

from the countershaft 10, which extends longitudinally of the machine and is journaled in bearings 11, 11. The motion of the countershaft 10 is transmitted to the drum shafts by means of duplicate pairs of gears 12, 13, the former fixed on the countershaft and the latter tight on the drum shafts. The counter shaft or driven shaft 10 is revolved from the driving shaft 14 through the medium of the pair of bevel gears 15 and 16, and the driving shaft has motion transmitted thereto by belt 17 and tight pulley 18, an idle pulley 19 being employed as usual.

In conjunction with the series of winding drums I employ a series of gage-plates 20, 21, 22, 23, each of which is provided with a set of perforations (see Fig. 4) increasing from a minimum as 24, to a maximum opening 25. These plates are identical in construction, except that the gage perforations may be graduated in size, and the description of one plate and its accessories will be sufficient for all of the series. The plates are each provided with a handle 26 and are adjustably supported in a slotted bracket 27, attached as by bolts 28 to the frame 7. The plate is held between an upper and lower block 29 and 30 respectively, against which the screw bars 31, 32, have a bearing. These bars are threaded into bosses on the bracket and may be turned by handles 33, 34, to hold the plate in either upper or lower adjusted position.

Each of the winding drums is provided with side flanges 35 between which a guide roller 36 may rotate. This roller is supported in a frame 37 in bearings 38, and the forked frame may be moved vertically by means of the screw bar 39 rotatably held in the bracket 40, which is securely attached to the frame 7. The bracket is formed with a flanged rib 41 about which the slotted portion 42 of the frame 37 fits, and in this manner the movement of the frame 37 is guided as it slides vertically. (Figs. 3, 6.)

Preparatory to being wound upon the first drum of the series, the wire to be drawn is "sharpened" i. e. it is reduced in diameter sufficient to permit its being inserted through the gage perforation selected in the first gage plate 20. In a machine as depicted in the drawings, approximately the first twenty or thirty feet are thus reduced. This sharpening is accomplished by means of the grooved rollers 43, 44 (see Fig. 4) lo-

cated at the front of the machine and supported by their shafts 45, 46 in the frame or uprights 47 fixed to the table top 8. The shafts 45, 46 are geared together by the 5 wheels 48, 49 and are provided with a series of complementary grooves 50 which gradually increase in diameter from left to right Fig. 4. Because of the geared connection the grooved rollers 43, 44 of course move in 10 different directions, and they are revolved through the medium of the shaft 46 of the lower roll 44. This shaft is driven or continuously revolved by a crank arm 51 on its end which is connected by pitman 52 with 15 the bell crank lever 53 on the transverse rock shaft 54. This rock shaft is supported under the table in bearings 55 and is rocked by a longitudinally reciprocating rod or bar 56 connected to the rock shaft by one arm of 20 the bell crank lever as 53'. The reciprocating bar or rod 56 extends toward the rear of the machine and its actuating mechanism is best seen in Fig. 5. A second transverse rock shaft 57 is supported under the table in 25 bearings 58 and the reciprocating rod is connected to this shaft by lever arm 59, while a second lever arm fixed to the rock shaft 57 as 60 connects the pitman 61 with the crank 62 of the shaft 63 which is supported in 30 bearing brackets 64 above the table top 8. This crank shaft receives motion from countershaft 10 through the medium of the gears 65, 66 (Fig. 3).

At the rear of the machine a vertically disposed receiving drum is designated by the number 67. This receiving drum is designed to receive the wire after it has been drawn to the required thickness, and it is supported as clearly seen in Fig. 5 from the 35 table 8 on bracket 68 in which the trunnion or shaft 69 is journaled and upon which the drum revolves as a center. Upon its closed bottom a beveled wheel 70 is provided and the bevel pinion 71 meshes with this wheel to 40 revolve the receiving drum. The bevel pinion 71 is fixed on the end of the transverse shaft 72 which passes through the frame 7 and is journaled in bearings 73. The shaft 72 is driven from the drive shaft 14 just 45 above it through the two meshing gear wheels 74 and 75, the former on the drive shaft 14 and the latter on the driven shaft 72. The driving shaft 14 is also provided with a balance or fly wheel 76 between the 50 bearing 73 and gear wheel 74, to steady and render regular the movement of the shafts.

A belt shifter 77 (Fig. 3) is adapted to shift the belt 17 from the idle pulley to the drive pulley and vice versa in starting or 55 stopping the machine, and this shifter may be actuated from any one of various positions of the machine by a series of handles 78 attached to the oscillatable bar 79 which extends approximately the length of the 60 machine and may rock in its bearings 80 at-

tached to the frame 7. The rock bar and shifter are pivoted together at 81 by means of a slotted connection as best shown in Fig. 5.

From the above description taken in connection with the drawings it will be noted that when the belt 17 has been shifted to the drive pulley and a suitable motor (not shown) is in motion the motion will be transmitted to the driving shaft and through the driving shaft to all the moving parts as has been described.

In the operation of drawing wire I employ a tool 82 (Fig. 7) as a convenient means for starting the wire about the winding 70 drums. This tool is attached to one end of the wire to be drawn by means of the chain 83 and pincers 84 (Fig. 1) and the tool may be attached to the drum, and to each drum successively as will be explained, by fitting 75 the tool in one of a series of radial recesses or notches 85 formed in the flange of each of the winding drums 1, 2, 3.

As before stated the wire to be drawn is first reduced to a minimum gage for a distance of twenty or thirty feet at its end depending upon the number of winding drums in use on the machine and the accompanying gage plates. This reduction of the gage as a preliminary is accomplished on the 80 grooved rollers by utilizing successively the grooves beginning with the large one and finishing with the smallest. The wire end is fed through the grooves, and withdrawn successively until the minimum gage is 85 reached, and the wire end is now ready to be inserted through the first gage plate 20. The wire end that has been thus "sharpened" 90 may now be threaded through the maximum opening 25 in first gage-plate 20. After the 95 end has been passed through the first plate, the pincers 84 are fastened to the end of the wire (Fig. 1) and the tool 82 is located in place on the first winding drum 1 as described. The power is now applied to the 100 machine and the winding drums revolved. After several turns have been wound about the first drum, the tool 82 is detached and the 105 wire is wrapped about the drum 1 so that enough wire will be left at the end to permit successive threading through plates 21, 22, 23 and winding about the drums 2, 3, the tool 82 being employed to take sufficient 110 turns about the successive drums. In this manner the thin end of the wire is passed 115 through the large opening in plate 20, wound about the drum 1, and then passed through a smaller opening in plate 21, wound about drum 2, passed through a still smaller opening in plate 22 and wound about drum 3, 120 and then after passing through the smallest hole or opening in the descending scale in plate 23 is wound about the receiving drum 67. The machine is now ready to draw the 125 wire, the driving power being applied, and 130

the several operating devices are set in motion. The wire is drawn through successively smaller gage openings in the gage plates and is thus reduced to the gage of the 5 last gage opening in the series through which it passes. The guide rollers 36 are brought down to proper position to guide the wire as it passes around the successive drums and they prevent the "turns" of the 10 wire from becoming loose or tangled on the drums over which they are passing.

By the adjusting means of Fig. 4 it will be seen that the gage plates may be adjusted vertically and laterally to bring any one of 15 the set of openings into line so that the wire may pass through the machine on a straight line.

The entire machinery while in operation runs smoothly and regularly, the balance or 20 fly wheel performing its function of steady- ing and regulating the momentum, and the separate devices are actuated continuously and simultaneously, the wire after being 25 acted on by the several devices, finally being wound upon the receiving drum 67. The belt may be thrown off at any time by any

of the handles 78 as described, thus stopping the movement of the machinery, and the machine may be again started in the same manner with equal facility.

30

Having thus fully described my invention, what I claim as new and desire to secure by Letters Patent is:

1. The combination with a supporting frame, a winding drum having side flanges, 35 and a vertically movable roller, of a sliding bracket supporting the roller, a screw bar held to the frame and revoluble therein and engaging the bracket, and means for guiding the sliding movement of the bracket. 40

2. The combination with a flanged winding drum having an axial opening with polygonal sides and a series of radial notches, of a wire stretching tool adapted to fit in 45 said opening and a selected notch.

In testimony whereof I affix my signature in presence of two witnesses.

GEORGE FECZKO.
